DESIGN FOR A CAR VENTILATOR

Nicholas L. Willer, Chicago, Ill., assignor to Rail-
way Utility Company, Chicago, Ill., a corpora-
tion of Illinois

Application December 24, 1934, Serial No. 54,579

Term of patent 14 years

To all whom it may concern:

Be it known that I, Nicholas L. Willer, a citizen of the United States, residing at Chicago, in the county of Cook and State of Illinois, have invented a new, original, and ornamental Design for a Car Ventilator, of which the following is a specification, reference being had to the accompanying drawing, forming a part thereof.

In the drawing,

Fig. 1 is a perspective view of a car ventilator showing my new design;

Fig. 2 is a side elevation thereof;

Fig. 3 is an end view, on an enlarged scale, of the car ventilator.

I claim:

The ornamental design for a car ventilator, as shown.

NICHOLAS L. WILLER.
